(No Model.)

J. T. GILBERT.
CHURN POWER.

No. 541,437.

Patented June 18, 1895.

UNITED STATES PATENT OFFICE.

JOHN TEXAS GILBERT, OF COLUMBUS, GEORGIA.

CHURN-POWER.

SPECIFICATION forming part of Letters Patent No. 541,437, dated June 18, 1895.

Application filed October 13, 1894. Serial No. 525,759. (No model.)

To all whom it may concern:

Be it known that I, JOHN TEXAS GILBERT, of Columbus, in the county of Muscogee and State of Georgia, have invented a new and 5 Improved Churn-Power, of which the following is a full, clear, and exact description.

The object of the invention is to provide a new and improved churn power, which is simple and durable in construction, very effective 10 in operation, and arranged to impart a reciprocating and turning motion to the dasher of the churn.

The invention consists principally of a shaft mounted to turn and to slide and adapted to 15 support a dasher, a head held revolvably on the said shaft, and a pitman pivotally connected with the said head and with the crank arm of the driving shaft.

The invention also consists in certain parts 20 and details, and combinations of the same, as will be hereinafter fully described and then pointed out in the claim.

Reference is to be had to the accompanying drawings, forming a part of this specification, 25 in which similar letters of reference indicate corresponding parts in all the views.

Figure 1 is a side elevation of the improvement. Fig. 2 is a front elevation of the same. Fig. 3 is an enlarged sectional side elevation 30 of the shaft-head and connection, and Fig. 4 is an enlarged transverse section of part of the improvement on the line 4 4 of Fig. 1.

In the drawings A represents the vertical main frame having perforated lugs α where- 35 by it may be secured to a support and provided at its upper and lower ends with forwardly bent portions or branches A', A², respectively, the latter of which the branch A² is provided with a short vertical standard A³, 40 as clearly seen. The branches A', A² are provided with aligned perforations or slide bearings in which is rotatively and slidely mounted a vertical shaft B, having at its lower end an integral enlargement B', provided with 45 a socket in its under side to permit of attachment to a churn dasher or the like, and in the periphery of said shaft B above the enlargement B' is formed a spiral groove B², adapted to be engaged by the tip of a set screw C,

screwing through the side wall of the slide 50 bearing C', in the lower branch A² of main frame A, as seen in Fig. 4, whereby said shaft B will when reciprocated in its bearings in the main frame A, also be caused to rotate.

The upper end B³ of shaft B is reduced as 55 seen in Fig. 3 and fits in a socket formed in a head D, in which it is free to turn but held against withdrawal by means of a washer E and pin E'. The upper portion of head D is forked and its forks are perforated to receive 60 a pin F which passes through an aligned perforation formed in the lower end of the re-turned downwardly-extending integral head G' of a pitman G, the lower end of which is pivotally connected to an arm H, secured on 65 a driving shaft I, journaled in a bearing formed in the upper portion of the upright standard A³ of the main frame.

A balance wheel J having a handle J', is mounted on the end of shaft I whereby the 70 latter may be conveniently turned to actuate shaft B, and impart reciprocatory and rotary movement thereto.

A churn power constructed as above de-scribed has many advantages for use over 75 other similar devices, being extremely simple and durable and owing to the peculiar move-ment, affording rapid movement of the shaft B with comparatively little expenditure of power. The construction of the main frame 80 and shaft B and of the pitman and the vari-ous connections is also very inexpensive com-pared with other devices.

Having thus described my invention, I 85 claim—

The combination of a main frame having upper and lower branches provided with slide-bearings, a shaft slidely and rotatively mounted in said bearings and provided with a reduced upper end, means for rotating said 90 shaft, a head having perforated forks and pro-vided with a socket to receive the reduced end of said shaft, a washer and pin for secur-ing said shaft against withdrawal from the socket, a pitman having a returned down-wardly-extending head provided with a per-foration registering with the perforations in 95 the forks, said pitman head being arranged

between the forks, a pin passed through the perforated forks and pitman head, an upright standard formed on the front end of the lower branch of the main frame and provided with a bearing at its upper portion, a shaft journaled in said bearing and provided with an arm pivotally connected to the lower end of the pitman, and a means for rotating said shaft, substantially as set forth.

JOHN TEXAS GILBERT.
